UNITED STATES PATENT OFFICE.

HENRY JOHN CUBITT KEYMER, OF GREAT YARMOUTH, ENGLAND.

POWER-HAMMER.

No. 926,987.

Specification of Letters Patent.

Patented July 6, 1909.

Application filed May 8, 1908. Serial No. 431,727.

To all whom it may concern:

Be it known that I, HENRY JOHN CUBITT KEYMER, a subject of the King of the United Kingdom of Great Britain and Ireland, and 5 residing at Gorleston-on-Sea, Great Yarmouth, England, have invented certain new and useful Improvements in Power-Hammers, of which the following is a specification.

10 This invention relates to hammers actuated by fluid pressure and it has for its object to provide an improved arrangement of valve mechanism and also to adapt the tool holder or socket to be rotated and reciprocated so as to serve as a rock or other drill.

The invention is illustrated in the accompanying drawings in which—

Figure 1 is a part elevation and part vertical section of the improved hammer: Fig. 2 20 is a plan (with the cover removed). Figs. 3, 4 and 5 are plan views of the disk valve seat, the valve diaphragm and the disk valve, respectively. Fig. 6 is a part sectional plan showing an arrangement in which the sleeve 25 actuates the valve or valves direct. Fig. 7 is a vertical section corresponding to Fig. 6 and shows the handle of the hammer formed hollow to serve as an oil reservoir. Fig. 8 is a detail view of the hammer handle. Fig. 9 30 shows in vertical section a modified arrangement wherein the oscillating sleeve is caused to actuate a piston valve or valves through the intermediary of levers. Fig. 10 is a horizontal section through the sleeve. Fig. 11 35 is a vertical section and Fig. 12 is an elevation at right angles to Fig. 11 showing an alternative arrangement for actuating the piston valve or valves, the oscillating sleeve being dispensed with. Figs. 13 and 14 show 40 in plan and elevation respectively the bush of the hammer piston cylinder.

As shown in Figs. 1 to 5, the cylinder A, having a portion extended to form a hammer guide A¹, and the tool socket holder A² form 45 the main structure. Outside the wall of the cylinder bush A^a is a passage or portway Z (shown particularly at Figs. 13 and 14) preferably slotted thereon and extending to the upper end of the cylinder to provide for passage of the fluid for the back or inward stroke of the piston F. Within the head or valve chest B is fixed a flat circular valve seating C with one port C² over the said passage Z, and another port C¹ over the end of the piston F. 50 A flat circular valve E works upon the seating C and has two separate inlet ports E¹ and E² and two separate exhaust or outlet ports G¹ and G²; thus, the inlet port E¹ and the outlet or exhaust port G¹ each operate over the port C¹ and the other ports E² and G² operate over the passage Z. In the forward stroke of the piston F the inlet port E¹ and the exhaust port G² are each open and the others covered, but are ready to act on oscillation of the valve E on the seating C, which latter motion 60 is caused by a projection L² on a sleeve L hereinafter referred to. Over the valve E is fixed a metal sheet H which presses upon the valve E to make a tight joint, and has two inlet ports H¹ and H² corresponding in position to the ports C¹ and C², so that when one inlet port of the valve E is open the other is closed. The positions of the ports thus combined are such that when the port E¹ is open the motive fluid passes through the ports H¹ 65 and C¹ and forces the piston forward to complete its outward stroke; at the same time the exhaust port G² is open over the passage Z and allows the exhaust fluid from the under side to escape. These ports remain open 70 until by the continued travel of the piston F the valve E is actuated and the position of the ports altered in which case the direction of travel of the piston F will be reversed. Corresponding to the two exhaust ports G¹ 75 and G², ports B¹ and B² are provided in the walls of the head casting B for escape of the exhaust fluid during the outward and inward strokes of the piston F. The piston F, piston rod F¹ and hammer I constitute one moving 80 body. In the hammer head is fixed a guide pin K which travels in a slot M in the hammer guide part A¹ of the cylinder or main structure. On the outside of the cylinder casting there are bearing surfaces whereon 85 works a sleeve L which has an inclined slot L¹ and to which is imparted a rocking or oscillating motion by the pin K in the hammer head engaging with said inclined slot L¹; the sleeve L being caused to oscillate according 90 to the form of the path of the slotted aperture L¹. This arrangement enables the motive power to be used expansively with a free exhaust. The upper end of the sleeve L has a projection L² adapted to pass through an 95 arcuate slot B³ in the head casting B, through a cut-away recessed edge C^x of the valve seating C and then fits into the exhaust port G² on the under side of the valve E, so that 100 on oscillation of the sleeve L, a rocking 105

55 A flat circular valve E works upon the seating 110

movement is imparted to the valve E upon the valve seating C. The tool socket holder A² carries a tool socket O, having a slight movement within the same so that the tool 5 which is fitted in and secured to the socket O in any suitable manner receives the impact of the hammer.

In a modified construction shown in Figs. 6 to 8, the upper end of the sleeve L has two 10 wings or projections L² and L³ which oscillate over or in front of a valve chamber E⁰ in a head casting D the base of which latter is fitted within the cylinder bush A^a and upon the flanged end of the main structure or cylinder casting A. In the head casting is a 15 power inlet Q for the admission of the motive fluid, said pipe having within it a throttle valve N resting upon a seat R in front of a starting pin S. On the ends of said pin is secured the trigger clamp S¹ (Fig. 8) which on being moved in one direction presses the valve N off its seat R, or on being moved in the opposite direction allows the valve to rest on its seat. When the valve N is raised 20 from its seat the power fluid passes by way of the passage Q¹ into the valve chamber E⁰ and thence through the port C¹ to the upper side of the hammer piston, or through the port C² and passage Z to the under side of the hammer piston. The piston valve or valves E¹ and E² have the pressure of the motive power 25 always upon their inner surfaces, which in the case of separate valves keeps them apart and forces each valve with its roller E³ or E⁴ 30 upon or in contact with the sleeve wings L² and L³. As shown in Figs. 6 and 7, the valve E¹¹ has been opened clear of the port C¹ so that the motive fluid can act upon the upper side of the piston, while the exhaust fluid will 35 escape by way of the passage Z and the port C² into the valve chamber E⁰, and thence by way of a port D² into the atmosphere. In a 40 position of the valves corresponding to that shown in Fig. 1, the sleeve L and wings L² and L³ will have been oscillated by the pin K (Fig. 1) operating in the slotted aperture L¹ and have actuated the piston valve or valves so as to open the port C² (Figs. 6 and 7) located over the passage way Z for the admission 45 of the motive fluid to the underside of the hammer piston and also to open communication between the ports C¹ and D¹ and allow the exhaust fluid from the piston head to escape into the atmosphere. The configuration 50 of the sleeve aperture L¹ in conjunction with the shape or form of the inside of the wings L² and L³ will control expansively the use of the motive fluid. For more convenient lubrication of the internal parts of 55 the mechanism, the handle of the head casting D is made hollow to serve as an oil reservoir and has a passage W connected to the power inlet Q, as shown particularly at Fig. 8.

In a further modified construction shown 60 in Figs. 9 and 10, the cap or cover contains

the piston valve or valves B¹¹ and B²¹ and a bush or liner C having two portways C¹ and C², the portway C¹ being close within the circle of the cylinder A, over the end of the piston and upon the opposite side from the passage Z, while the portway C² is directly over the said passage Z and outside the lining D. The duplex piston valve or two separate piston valves B¹¹ and B²¹ works or work within the bush C over the ports C¹ and C². In the 70 arrangement shown each piston valve is formed with an exhaust port B^X and a suitable recess B⁰ in the underside for engagement by the ends of levers E²¹ and E²² which pass through slots in the under side of the 75 valve chest in order to operate said valves. The levers E²¹ and E²² are pivoted upon pins F passing through joints made on the outside of the cylinder A. The end of each lever opposite that working within the piston valve 80 is provided with an anti-friction roller G in contact with a sleeve L, the upper portion of which sleeve is of cam-like formation so that on oscillation of the said sleeve L, the levers E²¹ and E²² will actuate the valves B¹¹ and B²¹ over the ports C¹ and C², and thereby effect the reciprocation of the hammer piston. The motive fluid which enters between the 85 inner ends of the valves B¹¹ and B²¹ at P causes the rollers G to contact with the cam-like upper portion of the sleeve L, which may be of such form as to allow of using the motive fluid expansively. 90

Figs. 11 and 12 show an arrangement for actuating the piston valves B¹¹ and B²¹, 100 wherein for the sleeve L (Figs. 9 and 10) are substituted levers M and M¹ having cam-like upper ends and pivoted at m and m¹ on the hammer guide A¹, the edges of said levers being of a form corresponding to that of the 105 aperture L¹ (Fig. 1) and operated by the pin K (Fig. 1) on the hammer head, in order to actuate the valve levers E²¹ and E²² (Figs. 9 to 12) or to actuate directly the valves E¹¹ and E²² (Figs. 6 and 7). 110

Having now described my invention what I claim and desire to secure by Letters Patent of the United States is:—

1. In a power hammer such as described, the combination with a working cylinder, of a valve chest having fitted therein a flat circular valve seating provided with ports communicating with said working cylinder, a flat circular valve with inlet and exhaust ports, a metal sheet or plate secured over 115 said valve and provided with inlets, and a rocking or oscillating sleeve having a projection to actuate said valve. 120

2. In a power hammer such as described, the combination with a working cylinder and a piston therein, of a valve chest, a valve or valves within said valve chest, and means for operating said valve or valves, said means comprising a rocking or oscillating sleeve, means for operatively connecting 125 130

said sleeve and valve or valves, and means carried by said piston for oscillating said sleeve.

3. In a power hammer such as described, 5 the combination with a working cylinder, of a valve chest, a valve or valves within said valve chest, and means for operating said valve or valves, said means including a rocking or oscillating sleeve and means for oper- 10 atively connecting said sleeve and valve or valves.

4. In a power hammer of the character described, the combination with a working cylinder and a piston therein, of a valve

chest, a valve or valves within said valve 15 chest, and means for operating said valve or valves, said means comprising a rocking or oscillating member, means for operatively connecting said member and valve or valves, and means carried by said piston and engag- 20 ing said member for oscillating the same.

In testimony whereof I have signed my name to this specification in the presence of two subscribing witnesses.

HENRY JOHN CUBITT KEYMER.
